US0D1011531S

(12) **United States Design Patent** (10) Patent No.: **US D1,011,531 S**
(45) Date of Patent: ** Jan. 16, 2024

(54) **MEDICAL IMAGING DEVICE**

(71) Applicant: **Siemens Healthcare GmbH**, Erlangen (DE)

(72) Inventors: **Roman Achleitner**, Nuremberg (DE); **Stefanie Gügel-Wild**, Langensendelbach (DE)

(73) Assignee: **Siemens Healthcare GmbH**, Erlangen (DE)

(**) Term: **15 Years**

(21) Appl. No.: **29/871,116**

(22) Filed: **Feb. 13, 2023**

Related U.S. Application Data

(62) Division of application No. 29/798,724, filed on Jul. 9, 2021, now Pat. No. Des. 982,161.

(57) **CLAIM**

The ornamental design for a medical imaging device, as shown and described.

DESCRIPTION

FIG. 1 is a front elevational view of a first embodiment of a medical imaging device showing our new design;

FIG. 2 is a back elevational view thereof;

FIG. 3 is a top plan view thereof;

FIG. 4 is a bottom plan view thereof;

FIG. 5 is a left-side elevational view thereof;

FIG. 6 is a right-side elevational view thereof; and

FIG. 7 is a top, front, left-hand side perspective view thereof.

FIG. 8 is a front elevational view of a second embodiment of a medical imaging device showing our new design;

FIG. 9 is a back elevational view thereof;

FIG. 10 is a top plan view thereof;

FIG. 11 is a bottom plan view thereof;

FIG. 12 is a left-side elevational view thereof;

FIG. 13 is a right-side elevational view thereof; and,

FIG. 14 is a top, front, left-hand side perspective view thereof.

The broken lines show portions of the medical imaging device that form no part of the claimed design.

1 Claim, 14 Drawing Sheets
